Inventor:

John Berg,
Bendixville, Pa., Chittenden, Vt.,
Assignee:

UNITED STATES PATENT OFFICE.

JOHN BERG, OF CHICAGO, ILLINOIS, ASSIGNOR TO METAL SPECIALTIES MFG. CO., OF CHICAGO, ILLINOIS, A CORPORATION OF ILLINOIS.

ELECTRIC CONNECTER.

Application filed November 1, 1920. Serial No. 420,947.

To all whom it may concern:

Be it known that I, JOHN BERG, a citizen of the United States, residing at Chicago, in the county of Cook and State of Illinois, have invented a new and useful Improvement in Electric Connecters, of which the following is a specification.

This invention relates particularly to electric connectors of the plug and socket type; and the primary object is to provide an improved connector which can be cheaply manufactured, and which has provision for securely connecting a conductor to a contact member with which the connector is provided.

The invention is illustrated, in its preferred embodiment, in the accompanying drawing, in which—

Fig. 1 represents an elevational view of a connector constructed in accordance with the invention; Fig. 2, a sectional view of the same, the section being taken as indicated at line 2 of Fig. 5; Fig. 3, a view of a contact-screw employed; Fig. 4, a section similar to Fig. 2, the screw being removed; Fig. 5, an end view of the member shown in Fig. 4; and Fig. 6, a sectional view illustrating a modification of the member shown in Fig. 4.

The connector comprises a member A which is of elbow form and which is composed of insulating material; and a clamping-screw device B which serves as a contact member and which also serves to clamping-ly secure the end of a conductor C in the member A.

The elbow A has an arm A' provided with a taper bore 1 which receives the conductor C, and an arm A² which constitutes a plug adapted to be received by the socket of another connector, the arm A² having a bore 2 which receives the clamping-screw B. The bore 2 has an inner end portion 2^a which is of angular form and has an outer portion 2^b which is somewhat larger and of cylindrical form. At the orifice of the bore 2 is provided a countersink 2^c. The taper bore 1 intersects the portion 2^a of the bore 2 near the inner end and extends beyond the bore 2, thus providing a depression 1^a adapted to receive the inner end of the conductor C. Thus, the inner ends of the bores are covered or blind ends. The conductor C is shown provided with an armor C' which is received in the outer portion of the bore 1.

The socket portion A² of the plug is

shown equipped with studs 3 which are adapted to be connected with bayonet slots in a companion connector. These studs may be in the form of small pins which are inserted in small sockets provided therefor in the operation of molding the member A.

The clamping screw device B comprises a screw member 4 and a tubular nut 5 which has threaded connection therewith. The member 4 has an angular shank-portion 4^a which fits in the socket portion 2^a of the bore 2, and has a threaded stem 4^b which receives the nut 5. The nut 5 is of cylindrical form and is threaded interiorly so as to screw onto the stem 4^b. The nut 5 has a flange or head 5^a, which is provided with a slot 5^b adapted to receive a screw-driver. The angular shank portion 4^a of the member 4 is provided with a transverse perforation 4^c, through which the conductor C extends.

It will be understood, from Fig. 2, that when the nut 5 is turned onto the screw or bolt 4, the bolt will be drawn toward the nut, and will force the wire conductor C against the wall of the bore 1. Thus, the wire will be clampingly secured in position, and will be more or less flexed at the point where it crosses the socket portion 2^a of the bore 2, so that the wire will be held very securely. The end portion of the nut 5 serves as a contact member for the electrical circuit.

It will be understood from the foregoing that the elbow A, which is of insulating material, may be molded without the necessity of introducing inserts; and thus it is possible to cheapen the operation of manufacturing the elbow and, at the same time, provide a better construction.

In the modification shown in Fig. 6, A³ represents an elbow similar to the elbow A. In this case, instead of employing the insert studs 3, the socket portion of the elbow is equipped with a thin metal sleeve, or ferrule, 6, having the metal struck outwardly at diametrically opposite points, as indicated at 6^a, thus providing the embossments or studs adapted for connection with the bayonet slots of a companion connector. In this case, the sleeve 6 serves as a reinforcement for the plug portion of the elbow and will prevent injury to the composition of which the elbow is composed.

The improved plug is admirably adapted

- for use in situations where considerable stresses are apt to be exerted on the conductor, or where, from the nature of the use, it is desirable to especially insure a secure 5 connection between the conductor and the contact member. The improvement obviates the necessity of using an insert metal socket with clamping-screws for securing the conductor to the connector.
- 10 While it is preferred to make the screw device B in the manner illustrated, that is, with the member 4 provided with an externally threaded stem, and the member 5 provided with an interiorly threaded socket 15 to receive said threaded stem, obviously the construction may be varied, if desired, it being understood that the important thing is to provide a two-part screw device which will serve as a means for clampingly securing 20 the conductor to the connector, and establish electrical contact between the conductor and the contact member.
- The foregoing detailed description has been given for clearness of understanding 25 only and no unnecessary limitation should be understood therefrom, but the appended

claim should be construed as broadly as permissible, in view of the prior art.

What I regard as new, and desire to secure by Letters Patent, is—

30 A device of the character set forth comprising a member of elbow form composed of insulating material and having one arm affording a plug provided with a bore having an inner end portion of angular cross-section and having at its outer end a countersink, the other arm having a bore intersecting and crossing the inner end portion of said first-named bore, said bores having blind inner ends, a screw in said first-mentioned bore having an angular head received in the angular portion of the bore, the head of said screw being provided with a transverse perforation, and a tubular nut journaled in said first-mentioned bore and 40 threaded on said screw, the extremity of said nut being provided with a flange resting in said countersink and said nut having a projecting portion adapted to serve as a contact member.

45 JOHN BERG.
